Aug. 26, 1952

G. W. MacCHEYNE

2,608,119

RATCHET WRENCH

Filed March 15, 1949

FIG. 1

FIG. 2

FIG. 3

FIG. 4

FIG. 6

FIG. 5

FIG. 7

FIG. 8

INVENTOR.
GEORGE W. MAC CHEYNE

BY Albert R. Hodges

ATTORNEY

UNITED STATES PATENT OFFICE

2,608,119

RATCHET WRENCH

George W. MacCheyne, Rochester, N. Y., assignor to Stromberg-Carlson Company, a corporation of New York

Application March 15, 1949, Serial No. 81,497

7 Claims. (Cl. 81—60)

1

This invention relates to a ratchet wrench, and more particularly to such a wrench especially adapted for use with relatively freely movable fasteners.

When the ordinary ratchet wrench is employed to tighten or loosen fasteners such as nuts or screws of relatively small size, which turn rather freely, difficulty is experienced in securing full advantage of the ratchet operation. When the handle of the wrench is moved backward to secure a new bite, the fastener has the tendency to rotate with the handle, with the result that little or no progress is made in rotating the fastener in the desired direction. If the fastener and hence the wrench itself are of relatively large size, this difficulty may be obviated by preventing such undesired rotation manually, the operator merely engaging the fastener or the wheel member of the wrench with the fingers of one hand while operating the handle of the wrench with the other hand. When relatively small fasteners are to be actuated, however, and the wrench itself is relatively small, it is difficult if not impossible for the operator conveniently to grasp the fastener or the ratchet wheel member of the wrench for the purpose of resisting rotation in the undesired direction, and the thread friction is too small to prevent such rotation. Such difficulties are especially pronounced in connection with the small fasteners and close clearances encountered in ultra-high frequency plumbing, as for example in the assembly and disassembly of wave guides or the like.

It is an object of the present invention, therefore, to provide an improved ratchet wrench incorporating as a part thereof an arrangement for preventing rotation of the fastener in the undesired direction as the wrench is operated in the customary manner.

It is a further object of the present invention to provide an improved ratchet wrench in which compact and simple means are provided for preventing undesired rotation of the fastener and which is adapted for one-hand operation by the operator.

Another object of the present invention is to provide an improved ratchet wrench in which a light and harmless contact with a surface either parallel with or normal to the axis of the fastener being turned prevents rotation in an undesired direction of the fastener during operation of the wrench.

In accordance with the present invention, there is provided, in a ratchet wrench adapted for rotating a fastener such as a nut or the like which is relatively freely movable with respect to a fixed member, a handle member. There is also provided a ratchet wheel member rotatively mounted in the handle member and being adapted to positively engage the fastener to be turned. A pawl member, carried by the handle member, is adapted to engage the teeth of the ratchet wheel member. There is also provided a foot member, which is adapted to engage the fixed member and to cooperate with the ratchet wheel member for resisting relative rotation in at least one direction between these two members.

2

In one preferred embodiment of the present invention, frictional engagement is provided between the foot member and the ratchet wheel member. In one modification of the present invention, a second pawl member is mounted on the foot member and adapted to engage the teeth of the ratchet wheel member, thereby to prevent rotation of the ratchet wheel member in a direction opposite to that of the rotation resulting from engagement of the first pawl member with the ratchet wheel member. In another modification of the present invention, the foot member comprises a helical spring fixedly mounted upon the ratchet wheel member and adapted frictionally to engage the fixed member, preferably in an area thereof adjacent the fastener being turned.

The above and other objects and features of the present invention will be better understood by referring to the following description taken in connection with the accompanying drawing, in which like components are designated by like reference numerals and in which:

Figs. 1 and 2 are respectively front and side elevations of a ratchet wrench in accordance with one embodiment of the present invention;

Fig. 3 is a partly disassembled front elevation of the ratchet wrench of Fig. 1;

Fig. 4 is an enlarged section taken on the line 4—4 of the view of Fig. 2;

Fig. 5 illustrates one application of the ratchet wrench in accordance with the present invention;

Fig. 6 is a partly disassembled front elevation of a modified form of the present invention; and

Figs. 7 and 8 are respectively front and side elevations of another modification of the present invention.

Referring to Figs. 1—4, there is shown a ratchet wrench 10 comprising a handle member 11, a ratchet wheel member 12, rotatively mounted with respect to handle 11 by means of side plates 13 and 14, which in turn are secured to handle member 11 by any suitable means, as for example by machine screws 15.

Member 12 is provided with an axially disposed opening 16 which is preferably hexagonal in shape. A removable member 17 is frictionally secured in opening 16. Member 17 is used when the wrench is to be employed for turning screws having a socket head, and is removed from the wrench for the tightening or loosening of nuts adapted to be directly engaged by opening 16.

As clearly shown in Fig. 3, a pawl member 18 is provided, and is disposed in a suitable slot 19 in handle 11. Pawl member 18 is maintained in engagement with the ratchet wheel 20 portion of member 12 by means of a spring 21.

Handle member 11 is also provided with a slot 22, into which is fitted a foot member 23 preferably formed of a wire-like rod having a relatively straight base portion 24, a first end portion 25 suitably looped to engage a groove in ratchet wheel member 12, and a second end portion 26 arranged to frictionally engage ratchet wheel member 12, as clearly shown in Fig. 4.

The operation of the ratchet wrench of Figs. 1-4 is clearly shown in Fig. 5, in which wrench 10 is illustrated being utilized to turn a fastener 27 of the type having a socket head. In this particular application, fasteners 27 are utilized to join sections 28 and 29 of a wave guide. Since fasteners 27 in this instance comprise screws of the socket-head type, wrench 10 is used with the member 17 in place in ratchet wheel member 12, the ends of member 17 protruding far enough on either side to permit ready engagement with the socket in fastener 27. As clearly shown in Fig. 5, foot member 23 touches or rests against a surface of wave guide 28, thus remaining relatively fixed in position as the wrench is operated. The contact between member 23 and ratchet wheel member 12 effectively prevents rotation in one direction of the fastener 27 which is being turned in the opposite direction. When rotation of fastener 27 in the reverse direction is desired, wrench 10 is merely faced about, so that the opposite end of member 17 engages fastener 27.

Fig. 6 illustrates a modification of the present invention, in which a foot member 30 is pivotally mounted with respect to ratchet wheel member 12 by any suitable means 31. Foot member 30 is provided with a second pawl member 32, which is suitably mounted, as for example on a flat spring member 33, to engage ratchet wheel portion 20 of member 12. In this modification, rotation of member 12 in the undesired direction is positively prevented by the cooperation of pawl 32 with ratchet wheel portion 20.

In Figs. 7 and 8, there is shown another modification of the present invention which is specifically adapted for use in turning fasteners protruding from a relatively large flat surface. As in the previously described embodiment, the ratchet wheel member 12 is rotatively mounted in the handle member 11, and is provided with an opening 16 into which may be inserted the rod-like member 17. For the purpose of preventing rotation of member 12 in the undesired direction, there are provided a pair of springs 34 and 35, preferably helically shaped. The ends of each of these springs are fixedly mounted or secured to ratchet wheel member 12 in any suitable manner, as for example by having a loop 36 formed in the end thereof and adapted for engaging a non-circular portion of ratchet wheel member 12, as shown in Fig. 7. The outer ends of springs 34 and 35 are arranged to frictionally engage the surface through which a fastener to be turned extends. The outer ends of these springs may be flattened and, if desired, provided with serrations whereby better to grip the adjacent surface and thus to remain immobile with respect thereto as the return stroke is made.

Although, in the embodiments illustrated in Figs. 1-5 of the drawing and described above, the foot members 23 and 30 are of a fixed configuration, it is within the scope of the present invention to provide the foot members with an adjustment which permits engagement thereof with the adjacent surface irrespective of the spacing above the surface of the fastener to be turned, as this dimension is varied between relatively wide limits. In general, however, such an adjustment is not required, since it is not essential in the successful use of the ratchet wrench of the present invention that fixed member 23 or 30 have its bottom or outer portion remain in full contact with the surface. Any contact of the foot member with the surface which prevents its substantial rotation as the wrench is operated is sufficient.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. In a ratchet wrench adapted for rotating a fastener such as a nut or the like which is relatively freely movable with respect to a relatively fixed member, a handle member, a ratchet wheel member rotatively mounted in said handle member and being adapted to positively engage said fastener reversibly in one of two positions, a pawl member carried by said handle member and adapted to engage the teeth of said ratchet wheel member, and a foot member adapted to engage said fixed member and to cooperate with said ratchet wheel member for resisting relative rotation in both directions between said foot member and said ratchet wheel member, whereby said fastener is rotated in a direction depending upon the relative position of said wrench in the fastener engaging position.

2. In a ratchet wrench adapted for rotating a fastener such as a nut or the like which is relatively freely movable with respect to a relatively fixed member, a handle member, a ratchet wheel member rotatively mounted in said handle member and being adapted to positively engage said fastener reversibly in one of two positions, a pawl member carried by said handle member and adapted to engage the teeth of said ratchet wheel member, a foot member adapted to engage said fixed member and being pivotally mounted with respect to said ratchet wheel member, and means for resisting relative rotation in both directions between said foot member and said ratchet wheel member, whereby said fastener is rotated in a direction depending upon the relative position of said wrench in the fastener engaging position.

3. In a ratchet wrench adapted for rotating a fastener such as a nut or the like which is relatively freely movable with respect to a relatively fixed member, a handle member, a ratchet wheel member rotatively mounted in said handle member and being adapted to positively engage said fastener, a pawl member carried by said handle member and adapted to engage the teeth of said ratchet wheel member, a foot member formed of material having a length great in comparison with its cross-sectional dimensions, said foot member being formed into a generally looped configuration such that one end of said loop bears against a portion of said ratchet wheel member with its outer surface while the other end of said loop bears against another portion of said ratchet wheel member with its inner surface, whereby said ratchet wheel member is frictionally engaged between the ends of said foot member.

4. In a ratchet wrench adapted for rotating a fastener such as a nut or the like which is relatively freely movable with respect to a relatively fixed member, a handle member, a ratchet wheel member rotatively mounted in said handle member and being adapted to positively engage said fastener, a pawl member carried by said handle member and adapted to engage the teeth of said ratchet wheel member, and a foot member formed of a material having a length great in comparison with its cross-sectional dimensions, said foot member being formed into a generally looped configuration such that one end of said loop bears against a portion of said ratchet wheel member with its outer surface while the other end of said loop bears against another portion of said ratchet wheel member with its inner surface, whereby said ratchet wheel member is frictionally engaged between the ends of said foot member, said looped configuration having a flattened portion formed therein in a position adapted to engage said fixed member.

5. In a ratchet wrench adapted for rotating a fastener such as a nut or the like which is relatively freely movable with respect to a relatively fixed member, a handle member, a ratchet wheel member rotatively mounted in said handle member and being adapted to positively engage said fastener, a first pawl member carried by said handle member and adapted to engage the teeth of said ratchet wheel member to provide rotation thereof in one direction, a foot member adapted to engage said fixed member and being pivotally mounted with respect to said ratchet wheel member, and means for resisting rotation of said ratchet wheel member in the opposite direction, said means comprising a second pawl member mounted upon said foot member and adapted to engage the teeth of said ratchet wheel member.

5 6. In a ratchet wrench adapted for rotating a fastener such as a nut or the like which is relatively freely movable with respect to a relatively fixed member, a handle member, a ratchet wheel member rotatively mounted in said handle member and being adapted to positively engage said fastener, a pawl member carried by said handle member and adapted to engage the teeth of said ratchet wheel member, and a helically shaped spring member fixedly mounted upon said ratchet wheel member and adapted to frictionally engage said fixed member.

10 7. In a ratchet wrench for rotating a fastener such as a nut or the like within the flange of a wave guide, said fastener being relatively freely movable relative to said flange, a handle member, a ratchet wheel member rotatively mounted in said handle member and adapted to positively engage said fastener, a pawl member carried by said handle member and adapted to engage the teeth of said ratchet wheel member, and a foot member made of wire formed into a generally looped configuration such that one end of said loop bears against a portion of said ratchet wheel member with its outer surface while the other end of said loop bears against another portion of said ratchet wheel member with its inner surface, whereby said ratchet wheel member is frictionally engaged between the ends of said foot member, said foot member having a flattened portion positioned to rest against the body of said wave guide when said ratchet wheel member engages said fastener in said flange.

35 GEORGE W. MACHEYNE.

REFERENCES CITED

The following references are of record in the file of this patent:

UNITED STATES PATENTS

Number	Name	Date
591,779	Hagstrom	Oct. 12, 1897
895,757	Hollandsworth	Aug. 11, 1908
1,070,569	Wilson	Aug. 19, 1913
45 1,508,033	Tiefenbacher	Sept. 9, 1925
1,912,045	Seagren	May 30, 1933

FOREIGN PATENTS

Number	Country	Date
50 823,990	France	Oct. 25, 1937